UNITED STATES PATENT OFFICE.

JOHN P. WEIS, OF NYACK, NEW YORK, ASSIGNOR TO METROPOLITAN SEWING MACHINE COMPANY, OF NYACK, NEW YORK, A CORPORATION OF NEW YORK.

TRIMMING MECHANISM FOR SEWING-MACHINES.

1,025,552.

Specification of Letters Patent.

Patented May 7, 1912.

Application filed September 19, 1905. Serial No. 279,116.

To all whom it may concern:

Be it known that I, JOHN P. WEIS, a citizen of the United States, residing in Nyack, county of Rockland, and State of New York, have invented a new and useful Improvement in Trimming Mechanism for Sewing-Machines, of which the following is a description.

This invention relates to trimming mechanism for sewing machines, and has special reference to trimmers to be applied to sewing machines for overedge stitching.

Among the objects of this invention may be noted the following: To provide a trimming mechanism by means of which the edge or edges of the work may be trimmed in advance of the stitching perfectly and effectively; to provide a trimming mechanism having a construction such that, when out of operation, it will act as a guide for the edge of the work; to provide a trimming mechanism which may be thrown into and out of operation while the machine is running and without affecting the stitching; to change or modifying the usual working of the sewing machine; to provide a trimming mechanism which may be readily detached from the machine without disturbing any part of said machine whatsoever; to provide a novel actuating mechanism for the trimmer, consisting of parts which may be readily separated for throwing the trimmer out of operation and quickly connecting it for starting the trimmer into operation all while the machine is in operation and at the will of the operator, and without affecting the usual functions of the machine, to provide means for adjusting the trimmer-blades relatively; to provide means for effectively disposing of the trimming or edge which is cut from the work; to provide means by which the elevation of the lower blade relatively to the surface of the cloth-plate may be gaged, determined, and effectively set; and to provide various other details of improvement hereinafter described and set forth.

With the above objects in view, the invention consists in the parts, features, combinations of elements and mechanisms hereinafter described and claimed.

In the drawings forming part of this description: Figure 1 shows in rear elevation so much of a sewing machine as is

deemed necessary to illustrate my invention, the frame of the machine being shown in dotted lines and the important features in full lines; Fig. 2 is a section of the cloth-plate taken on the line 3—3 of Fig. 1; Fig. 3 is a top plan of the cloth-plate shown detached from the machine; Fig. 4 is a vertical cross-section of the machine taken just back of the presser-foot and showing the details of the trimming mechanism; Fig. 5 is a top plan of the cloth-plate, similar to Fig. 3, but showing the presser-foot in position, the trimmer-blades in operative relation thereto and the guard-plate closed and in operative position; Fig. 6 is a rear elevation of Fig. 5, the trimmer blades, however, being omitted; Fig. 7 is a view similar to Fig. 4, but showing certain portions in section in order to clearly illustrate the detachable connection between the driving-shaft and the trimming mechanism; Fig. 8 is a side elevation of the trimming mechanism detached and showing certain details of construction; Fig. 9 is a front elevation of the trimming mechanism of Fig. 8; Fig. 10 is a top plan view of the trimming mechanism of Fig. 8; Figs. 11, 12, 13 and 14 are detail views of portions of the trimming mechanism hereinafter described.

Referring to the drawings, the numeral 1 indicates generally the frame of the machine, 2 the bed-plate thereof, 3 the driving-shaft, 4 the combined balance-wheel and driving-pulley, 5 the pitman connection between the usual eccentric on the driving-shaft and the needle-arm for actuating the needle 7. The presser-bar is indicated at 8, having the shank-portion 9 of the presser-foot clamped thereto in usual manner, the foot 10 being pivoted to said shank by means of the needle-bar 6, which carries the needle 7. In the side 15 of the cloth-plate 11 is provided with the rear, inclined, chute-portion 12 and a transverse, diagonally-disposed groove 13 for guiding the thread to the spreader, said groove being covered by a guard 14 which extends nearly across said slot laterally, leaving a narrow slot at the rear edge as shown in Fig. 2. In the side 15 of the cloth-plate an opening 16 is provided partially covered by upturned end 17 of the guard-plate 14, at its other end said guard-plate being provided with an upturned end 18, the function of which will be hereinafter

described. The pull-off mechanism, including the pull-off arm and thread-grip, is indicated generally by 19, this mechanism acting upon the spreader-thread to control the supply thereof to the spreader 20, the latter coöperating with the looper 21 and the needle 7 to produce an overedge, two-thread, chain-stitch. The cloth-plate 11 is provided with a depression 22 in which is 5 an opening 23, through which the spreader works to carry the loop of needle-thread across the edge of the work. The opening 23 is covered by a guard-plate 24, pivoted at 25 in the depression 23 of the cloth-plate, 10 said guard-plate having an enlarged head 26 provided with a notch 27, through which the spreader works, and with an upturned end 28 coöperating with the upturned end 18 of the guard-plate 14. These two portions 18 and 28, coöperating to deflect the trimming into the chute 12, and the end 18 of the guard-plate also acting as a guide for the trimmed edge of the work and is so constructed as to avoid drag upon said edge 15 and snagging the same. When in position, the guard 24 is held by an eccentric 29, pivoted to the cloth-plate by the screw 30; and the guard is provided with the upwardly-extending overhanging-portion 31, 20 which acts as a finger-piece by means of which the guard-head 26 may be lifted over the holding eccentric 29, and also has the function of guarding the fingers of the operator from contact with either the needle 25 or the trimming mechanism. The extension 32 on the guard coöperates with the throat-plate 33 and with the undercut portion 34 thereof. The throat-plate 33 is provided with the usual feed-slots 35 and with a slot 36 in which the trimmer-blades work, and in advance of said slot with a tongue 37 over which the stitches are formed and from which they slip as the feed takes place. A holding-plate 8 is secured to the cloth-plate 40 by a screw 39 in advance of the throat-plate and aids in holding the same in place, the said throat-plate at its rear end being held by a screw 40 and a stitch-adjusting mechanism generally indicated by 41. 45 operating with the rear end of said throat-plate for the purpose of adjusting the same to create drag upon the work; all as set forth in my patent granted April 25, 1911, No. 990,411.

45 42 is a sight-hole in which may be placed a lens, through which the feed-adjusting mechanism may be viewed in order to properly adjust the length of the stitch.

43 is the feed-rocker journaled to the bed-plate at 44 and actuated in any usual manner from the driving-shaft, said rocker carrying at its upper end the feed-bar 45 which in turn, at its forward end, has secured to it the feed-dog 46, the vertical rise 60 and fall of said dog being accomplished by

means of the pivotally connected strap 47, driven from an eccentric on the driving-shaft 3, all as usual.

The trimming mechanism includes the bracket 48 secured to the front edge of the bed-plate, the latter being provided with a detachable and adjustable front-plate 49 held in position by the screw 50 which passes through the slot 51, the position of this plate on the bracket 48 providing a seat 52 in which is set the lower edge of the trimmer-frame 53, the flange or reduced portion 54 being provided to coöperate with said seat 52. In the face of the bracket 48 transverse grooves 55 are formed which receive the lugs 56 on the back of the trimmer-frame 53, this means resulting in properly centering the trimmer in the machine and holding the same from vibration or movement in the latter. Bracket 48 is also provided with the opening 57, through which operates the telescopic pitman for actuating the trimming mechanism. The trimmer-frame is also provided with the parallel arms 58, in the upper end of which is journaled the bell-crank trimmer-lever, as at 59, the depending arm 60 of said lever having pivoted thereto the headed rod 61, which enters the tubular strap 62, which surrounds the eccentric 63 on the driving-shaft 3. It will thus be seen that the connection between the driving-shaft and the trimmer-lever is telescopic and that the rod 61 may freely slide within the sleeve 62. However, for actuating the trimmer-lever, the rod 61 and sleeve 62 must be rigidly connected so that the movement of the eccentric on the driving-shaft may be communicated to the trimmer-lever. This is accomplished by pivoting upon the head of the rod 61 a bell-crank latch-lever 64, one arm of which provides a handle and the other arm of which is extended into the hook 65 which drops over and engages a pin 66, carried by the tube 62, this being conveniently accomplished by clamping upon the tube 62 a collar 67, carrying said pin 66. The tube carries in it a coiled spring 68, which is held from sliding therefrom by means of a pin 69 passing through the wall of the tube and between two of the coils of said spring. The function of this spring is to eject the rod 66 partially from the tube and thus automatically depress the trimmer-blade carried by the arm 70 of the trimmer-lever, said blade being indicated by 71. This operation will occur instantly the latch-lever 64 is raised from engagement of the pin 66 to detach the sectional pitman or strap 61-62, and the downward movement of the trimmer-blade is limited by the stop-projection 72 on the upper end of the trimmer-frame, this projection standing normally under the arm 70 of trimmer-lever and providing a rest for said arm when the trimming mecha- 100 105 110 115 120 125 130

nism is out of operation and constituting a properly disposed stop for limiting the downward movement of the trimmer-blade so as to position the cutting-edge 73 of said 5 blade just below the complementary edge of the stationary ledger-blade 74, carried by a stationary part 75 of the trimmer-frame and held in place by the cam-lever 76, pivoted at 77 to said frame, the upper end of said 10 lever 76 engaging the ledger-blade 74 and firmly holding it in adjusted position. When the trimmer-blade 71 is thus lowered, its upper broadened end 78 operates as a guide for the edge of the work, thus 15 providing a means, when the trimming mechanism is thrown out of operation, for guiding the edge of the work properly relatively to the stitch-forming mechanism and preventing said work from leaving its proper 20 position for application of the stitching. It will thus be seen that the trimming is done or accomplished by an overhanging trimmer-blade operating from below up through the cloth-plate and that by thus 25 disposing the trimmer-blade, and having all the actuating parts of the trimmer mechanism below the cloth-plate, an absolutely unobstructed surface of the cloth-plate is provided for manipulation of the work, thus 30 avoiding any interference with the proper disposition of the work and manipulation of the latter by the operator. The trimmer-frame 53 is provided with the oppositely extending lugs 79, which are engaged by 35 and enter notches 80 in the latch-levers 81, pivoted on opposite sides of the bracket 48, as at 82. The journal 59 of the trimmer-lever is screw-threaded at one end, as at 59^a, Figs. 9 and 10 and has applied to said screw- 40 threaded portion outside the frame the clamping-nut 83 which, when loosened, permits the manipulation of the adjusting nut 84 for moving the said journal laterally in the trimmer-frame to thus cause the trim- 45 mer-blade 71 to bear with more or less pressure against the side of the ledger-blade 74.

To the top of the trimmer-frame, close beside the ledger-blade 74, is secured a gage or indicator 85, the horizontal portion of 50 which is seated in a depression of said frame and securely held by means of the screws 86 and the forward end of which is provided with the upturned and curved finger 87, which extends into engagement with the ledger-blade 74 at its rear edge to operate to gage the position of said ledger-blade 55 when the latter is placed in the machine and pushed upwardly until it has reached the proper position for coöperation with the trimmer-blade 71; that is to say, for proper coöperation with the trimmer-blade, the ledger-blade 74 should have a certain fixed operative position which will place its upper edge substantially flush with the 60 throat or cloth plate, and in order to pre-

vent said ledger-blade from being projected too far through said cloth or throat plate, the gage or indicator 85 is provided, which is set so as to place its finger 87 in position so that the ledger-blade 74 will be set in the 70 proper position by the operator. This gage or indicator has been found to be quite convenient and important, owing to the fact that, when the ledger-blade is removed from the machine for grinding and sharpening, 75 an inexperienced operator, in replacing the said blade, is quite liable to misplace or mis-set said blade, and thus materially affect the trimming function, or cause the said blade to interfere with the bottom of the 80 work. With the gage or indicator, the operator has only to slide the ledger-blade until it is flush with the top of said gage and then clamp the said blade in position. To further protect the operator from injury by the 85 trimming mechanism, the presser-foot is provided, at its forward end, with a guard 87^a, which extends vertically, as shown in Fig. 7, and is provided with a shank-portion 88, secured to the toe of the presser-foot by a 90 screw 89.

Having thus described the details of my invention, the following description of operation will be readily understood: With the parts shown in the position of Fig. 4, the eccentric on the driving-shaft will actuate the trimmer-lever so as to reciprocate the trimmer-blade beside the ledger-blade, and the overhanging cutting edge of said trimmer-blade will permit the work to pass 100 theretunder, resulting in effectively trimming the edge of the work in advance of the stitching. When it is desired to throw the trimming mechanism out of operation, the operator has simply to depress the operating arm of the latch-lever 64, thus disengaging its hook 65 from the pin 66 on the tubular portion 62 of the pitman, this operation resulting in permitting the spring 68 in said tube to force the rod 61 partially 105 from said tube; thus depressing the arm 70 of the trimmer lever into engagement with its stop 72, thus depressing the cutting-edge 110 of the trimmer-blade below the complementary edge of the ledger-blade and holding the same in proper position for enabling said trimmer-blade to act as an edge-guide for the fabric. From this time the eccentric on the driving-shaft 3 will have no effect upon the trimmer-lever, but will 115 merely impart idle movement to the strap 62. The stop 72 also operates as a limit for the outward movement of the rod 61 relatively to the tube 62, thus preventing the entire detachment of said rod from said tube 120 and also preventing the two parts of the strap from being thrown into such position that they may not be readily connected for operation of the trimming mechanism at will. With the trimming mechanism thrown 125

out of operation, the machine will perform its usual functions, but the edge of the work will not be trimmed. When the operator desires, the trimmer may be thrown into operation again by merely pushing the lower 5 arm 60 of the trimmer-lever forward so as to compress the spring within the tube 62 and thus bring the hook of the latch-lever 64 in position so that, by manipulating said lever, the hook can be passed over the pin 66 on the tube, thus connecting the strap portions so that the eccentric will properly operate the latter for driving the trimmer-lever. When the operator desires he may 10 detach the entire trimming mechanism from the machine by first unhooking the latch-lever from the pin 66 on the tube of the pitman and then lifting the levers 81 from the pins 79 and then by slightly tilting the trimming mechanism toward him and lifting 15 the trimmer-frame from the bracket, so as to disengage the lower edge 54 and lift the same from the seat 52 of said bracket. This can be done at any time even during the 20 operation of the machine, without affecting the usual functions of the latter.

From the above description, it will be seen that many advantages are derived from applicant's construction, among which may 25 be noted the following: A compact, simple and reliable trimming mechanism is produced which may be readily detached from the machine at the will of the operator, irrespective of whether the machine is running or not; the trimming mechanism may 30 be thrown into and out of operation while the machine is running, thus enabling the operator to trim at will; the trimmer-blade may be adjusted relatively to the ledger-blade by a simple manipulation of a binding and an adjusting nut; the ledger-blade may be set in proper position beyond peradventure of misadjustment; the trimmer-blade may be so constructed as to operate 35 upon the thickest and the thinnest work by merely altering the size of the space below its trimming edge and between the latter and its shank; when the trimmer-blade has been thrown out of operation, it then becomes 40 a guiding-device which is found to be extraordinarily convenient and very valuable, owing to the fact that it is next to impossible, in high-speed machines, to properly guide the work to keep the stitching straight, and the provision of this mechanism completely eliminating all necessity for providing guides on the cloth-plate; the fingers of the operator are prevented from contact with the trimmer-blades by providing 45 the guards, both on the presser-foot and the cloth-plate, and the guard-plate having the particular construction described provides means for deflecting or shunting the trimming so as to prevent the same from 50 getting in the way of the stitching mecha-

nism after the edge of the work has been properly trimmed, the devices described, viz., the upturned fingers 28 and 18 on the guard and guard-plate, respectively, coöperating to perform these functions.

Having thus described my invention, 70 what I claim and desire to secure by Letters Patent is:

1. In combination with a sewing machine, having a cloth-plate provided with a chute 75 in rear of the stitching position, a trimming mechanism operating to trim the edge of the work, and means for shunting the trimmed edge from the stitching position into the said chute.

2. A trimming mechanism including, in combination, trimmer-blades; an eccentric on the driving-shaft of the machine; a strap engaging said eccentric having a tubular extension; a rod carried by the trimming mechanism in position to enter said tubular extension; a spring within said tubular extension normally tending to force the rod from the latter; means for holding the telescopic parts operatively together; and 80 means whereby the parts of the telescopic connection may be detached during the operation of the trimming mechanism.

3. In combination with a sewing machine, trimming mechanism secured thereto below the work-plate and having a trimmer-blade, means for projecting said blade through the work-plate for trimming, and means whereby the trimmer-blade may be thrown out of operation and so located as to operate as a work-guide.

4. A trimming mechanism including a reciprocating trimmer-blade, means for throwing the same into and out of operation at will; and a stop for positively locating 105 the trimmer-blade, when it is thrown out of operation, with its body-portion in position to operate as an edge-guide for the work.

5. A trimming mechanism including, in 110 combination, trimmer-blades; an eccentric on the driving-shaft of the machine; a strap engaging said eccentric; a telescopic connection between said eccentric strap and one of said blades, including a rod pivoted to the 115 trimming mechanism; means for holding the telescopic parts operatively together including a latch mounted concentrically with the pivot of said rod; and means connected with said latch for manipulating the latter, 120 and accessibly presented to the operator whereby the parts of the telescopic connection may be released during the operation of the trimming mechanism.

6. A trimming mechanism for sewing 125 machines comprising a trimmer-frame; a ledger-blade and a trimmer-blade carried by said frame; a holding-bracket for supporting the trimmer-frame; said bracket being provided on opposite sides with pivoted 130

latches, and the trimmer-frame being provided on opposite sides with laterally-extending pins for coöperating with said latches, whereby when the trimmer-frame is set upon the holding-bracket the latches may be turned into engagement with the pins to hold the parts firmly together.

7. A trimming mechanism comprising a trimmer-blade and a ledger-blade, and means coöperating with the ledger-blade by which to gage the proper operative position thereof relatively to the trimmer-blade, said

means including a plate fixed relatively to the ledger-blade and having an upturned finger located adjacent the ledger-blade and 15 coöperating with the latter.

In testimony whereof I have hereunto signed my name in the presence of two subscribing witnesses.
